CLAIM

The ornamental design for a solar cell, as shown and described.

DESCRIPTION

FIG. 1 is a top perspective view of a solar cell showing my new design;

FIG. 2 is a partial enlarged view thereof, taken from the indicated area in FIG. 1;

FIG. 3 is a top plan view of the solar cell FIG. 1;

FIG. 4 is a bottom plan view thereof of the solar cell of FIG. 1;

FIG. 5 is a front side elevation view thereof;

FIG. 6 is a left side elevation view thereof;

FIG. 7 is a right side elevation view thereof;

FIG. 8 is a back side elevation view thereof; and,

FIG. 9 is a partial enlarged view thereof, taken from the indicated areas in FIGS. 5, 6, 7 and 8.

(Continued)

The broken lines indicate the bounds of the claimed design
and form no part thereof.

1 Claim, 6 Drawing Sheets
